(57) **CLAIM**

The ornamental design for a tablecloth with magnetic retainers, as shown and described.

DESCRIPTION

FIG. 1 is a bottom, front and side perspective view of the tablecloth with magnetic retainers;

FIG. 2 is a front side view thereof, wherein a back side view is a mirror image thereof;

FIG. 3 is a right side view thereof, wherein a left side view is a mirror image thereof;

FIG. 4 is a top side view thereof;

FIG. 5 is a bottom side view thereof; and,

FIG. 6 is an enlarged detail view of the area circumscribed by broken line within FIG. 3.

1 Claim, 6 Drawing Sheets
